UNITED STATES PATENT OFFICE.

JOSEPH P. WILD, OF WAUKESHA, WISCONSIN.

TUMBLING AND SAND-BLAST CLEANING MACHINE.

Application filed July 6, 1923. Serial No. 649,819.

To all whom it may concern:

Be it known that I, JOSEPH P. WILD, a citizen of the United States, residing at Waukesha, county of Waukesha, and State 5 of Wisconsin, have invented certain new and useful Improvements in Tumbling and Sand-Blast Cleaning Machines, of which the following is a specification.

My invention relates to machines used for 10 cleaning castings and for similar purposes, in which is a rotating drum where the articles to be cleaned are placed and agitated, and a blast mechanism for delivering sand or other abrasive to the articles to be cleaned 15 while being agitated; and it has for its object to improve machines of this kind in the manner which I will point out in the following specification.

In the accompanying drawings wherein I 20 have illustrated the preferred embodiment of my invention—

Figure 1 is a side view of a cleaning machine embodying the invention, as it appears when closed and in operation.

Fig. 2 is a front end view of the machine.

Fig. 3 is a side elevation representing, in full lines, the machine with the end which constitutes the door to the rotating drum swung to one side to expose the interior of 30 the drum, and, in dotted lines, the drum tilted to discharge its contents.

Fig. 4 is a top plan view of the apparatus with the parts occupying positions shown in Fig. 1.

Fig. 5 is a longitudinal sectional view on the line V—V of Fig. 4.

Fig. 6 is a rear end view of the machine.

Fig. 7 is a detail end view of the sand trap or collecting receptacle.

Fig. 8 is a broken view developed in a plane illustrating the casing surrounding the drum, and the means for separating and grading the material that collects therein.

Figs. 9 and 10 are perspective diagrammatic views illustrating the grading and collecting means in the surrounding casing.

In the accompanying drawings, 2 indicates the tumbling drum into which the articles to be cleaned are inserted through 50 its open front end, which while the drum is in operation, is closed by a door or movable closure 6. The drum is the frustum of a cone in shape, and is preferably formed of metal, its front end being open and its rear 55 end closed by a wall or plate 5. A portion, 4, of the drum, toward the large or head

end thereof, is surrounded by a casing 7, set off therefrom a suitable distance to form a chamber 44, the purpose of which will be later described. The part of the drum extending beyond the casing 7, toward the rear, is indicated by 4'. A section, 3, of that part of the drum designated 4 is perforated, thus establishing communication between the interior of the drum and the chamber 44. 60 65

One or more tires 8, two being shown in the drawings, are secured to the periphery of the drum, and these are adapted to run in a trough formed to receive them in a cradle 12. A series of rollers 13, mounted on shafts 14, are arranged in the channel of the cradle 12, in engagement with which run the tires 8 whenever the drum is involved. The tires are preferably separated from each other by spacing pieces 10 and the casing wall 7 rests upon other spacing pieces 11 secured to the periphery of the drum and preferably being in the chamber 44. Connected with the drum, preferably by being secured to one of the tires 8, is a 70 75 bevel gear ring 9.

15 indicates the main frame for supporting the drum. It comprises a pair of posts on opposite sides of the drum, carrying bearings 16 at their upper ends, in which are mounted trunnions 17 projecting laterally from the cradle 12. The trunnions freely turn in the bearings 16, permitting the drum and the cradle 12 to move from the normal working position represented in 80 Fig. 1, to the discharging position represented in dotted lines in Fig. 3.

A shaft 18, supported in one of the trunnions 17, serves as the power shaft through which the drum is rotated. It carries a pulley 20 for a belt connecting it with any suitable source of power, and a pinion 19 in mesh with the gear ring 9.

21 indicates a floor stand or support for the rear end of the drum; and 22 a post or support to which is hinged, at 23, a bracket 26 carrying the door or closure 6 for the front end of the drum. This closure is preferably of conical shape and is formed at its center with a hub 24 that turns in a bearing 25 carried by the bracket 26. The hub 24 has formed through it an opening 32 in which is supported the nozzle 31 through which is discharged the sand or other abrasive used in cleaning the articles within the 110 tumbling drum. The sand is stored in a hopper or box 27 that delivers into a mixing

chamber 30, communicating with the sand nozzle 31, and into which projects an air nozzle 28 that is connected by hose 29 with any source of supply of air under pressure. 5 The nozzle 31 is so inclined as to direct the stream of air and abrasive carried thereby against the material that may be in the drum to be cleaned while being tumbled and agitated by the rotation of the drum.

10 At the rear end of the drum and secured to the exterior of the closing plate 5 is a tubular hub 33 mounted in a bearing 35 which is secured by bolts 38 to a separable supporting piece 37 that is adapted to rest 15 upon the upper end of the floor stand 21 when the drum is in working position as indicated in Fig. 1. When the drum is tilted for discharge, as indicated by dotted lines in Fig. 3, the supporting piece 37 leaves the floor stand as shown by the drawings. 20 The support for the rear end of the drum serves to arrest and so support the drum that it is not only in position to be rotated but is also in correct position to receive the swinging closure or door 6 without necessitating manual adjustment to one 25 position or another to cause the door to match the open end of the drum, as would be the case if the drum were not provided with means for arresting it in a fixed or determined position after it has been tilted.

The rear wall 5 is perforated at 34, so 30 that there is communication between the interior of the drum and the tubular hub 33. This hub and its bearing are surrounded by a housing 36 with which is connected an air trunk 39 leading to a chamber 40, supported by the trunnion 17 of the cradle 12 that is opposite the trunnion 40, through which passes the drive shaft 18. A nozzle 41, coaxial with the trunnion 17, 45 extends outward from the air box 40 and enters the end of an air trunk 42 that leads to some suction apparatus, not illustrated. The housing 36, the air pipe 39, the air box 40, the nozzle 41, and pipe 42 constitute an 50 exhaust duct through which the dust-laden air from the tumbling drum is carried away. The arrangement is such that a working connection is maintained at 41, 42, whatever be the position to which the drum is adjusted.

The general operation of the machine will be readily understood from the foregoing 55 description. The door or closure 6 is swung to one side as represented in Fig. 2 and the articles to be cleaned are placed within the drum and the door closed and secured. The drum is then rotated, causing the articles to be tumbled and agitated. While this is taking place a blast from the nozzle 31 carrying sand or other abrasive material is discharged against the articles to assist in cleaning them, in a manner well known 60 in the art. The main body of the abrasive,

along with the heavier particles of matter removed from the articles being cleaned, passes through the perforated portion 3 of the drum into the chamber 44 where it is taken care of in a manner which I will presently describe. The dust and lighter material that fills the atmosphere within the drum is taken off through the exhaust duct and disposed of in one way or another as may be found desirable. After the agitating and cleaning action has been carried on sufficiently long to clean the articles, the rotation of the drum is stopped, the door 6 is opened, and the drum tilted to the position represented in dotted lines in Fig. 3, 70 so that its contents are discharged, as into a barrow B placed between the posts of the frame 15 to receive it. By making the drum in the form of a frustum of a cone the larger end of which is entirely open for charging and discharging purposes, I find that it discharges much more readily than if the drum were cylindrical, or had an opening of contracted size, for no matter how badly the articles treated become tangled one with the other, or whatever be their size and shape, they will freely discharge from the drum when it is tilted, as represented in Fig. 3.

In connection with the drum which I have described I combine means for sifting and screening the loose material that passes through the perforated portion 3 of the drum into the chamber 44 surrounding the larger end thereof and formed by the enclosing casing 7.

Referring particularly to Figs. 8 to 10 of the drawings in which the interior arrangement of the chamber 44 is represented and where the direction of rotation of the drum 105 is indicated by broken arrows, it will be observed that directly following the perforated section 3 of the drum there is a screen 45, located between the periphery of the drum 2 and the cylindrical wall of the casting 7, and extending from a line on the front wall 63 of the chamber 44 close to the section 3, nearly to the rear wall 64 thereof, leaving a space, 54, between the end of the screen and such rear wall. The screen 45 110 is inclined, that is to say, its forward end is nearer to the perforated section 3 of the drum than is its rear end, with the result that the material which passes through the perforations 3 into the chamber 44 is directed, as the drum rotates, against the screen and slides along the same from its forward to its rear end, the fine material passing through the screen and the coarser passing over the same and through the space 54, where it falls upon a second screen 48 that is reversely inclined to screen 45, its forward end being in engagement with the rear wall 64 of the chamber, and its rear end terminating short of the front wall 63. 115 120 125 130

An imperforate deflecting plate or wall 46 is located adjacent to the perforated section 3 of the drum and extends from the rear wall thereof inwardly with an inclination the reverse of that of the screen 45. The material which passes through the rear part of the perforated drum section 3 falls upon this plate 46 and is by it directed to the screen 45. A second imperforate deflecting plate 47 is mounted behind the screen 45 and inclined reversely thereto, its forward end joining the rear end of the screen 45 and its rear end connecting with a wall 50 that is parallel with the front wall 63 of the chamber 44. Between the walls 50 and 63 is a passage 51 leading to an opening 52 into a duct or spout 55 that delivers to the sand or abrasive box or trap, 56. A third imperforate wall, 49, is directly behind and parallel with the second screen 48. There is formed a pocket, 53, bounded by the wall 47, the wall 50, and the screen 48, in which collects the coarse material that will not pass through the screens 45 or 48.

The operation of the parts just described is as follows: As the drum revolves, in the direction indicated by the broken arrows, the abrasive and the loose material removed from the articles being cleaned will sift through the perforate portion 3 of the drum and enter the screening chamber 44. The material entering such chamber first comes into engagement with the screen 45 and is caused to slide over the front face thereof, a considerable portion of the finer particles passing through the screen, to be caught by the imperforate wall 47 and directed by it into the channel 51, whence it passes through the opening 52 and into the spout or duct 55 by which it is eventually directed to the trap 56. Such of the material as does not pass through the first screen 45 goes over its end, at 54, and passes to the second, reversely inclined, screen 48, along the face of which it is caused to slide. Fine material passes through this screen and is caught upon the second imperforate wall 49 by which it is directed to the opening 52 and into the duct or spout 55. The coarse material, which does not pass through either of the screens, collects in the pocket 53. When the drum has turned sufficiently far, as to the position indicated in Fig. 10, the coarser material in the pocket 53 falls against the rear face of the imperforate plate 47, and is by it directed toward the opening 54, reaching which it falls against the rear face of the plate 46 and is by it directed into a collecting box 61 for the coarse stuff. It will thus be seen that there is an automatic screening and grading of the material that passes through the perforate section of the drum and into the chamber 44. The coarser material, as has been stated, is delivered into the collecting box

61 from which it may be removed, automatically or otherwise, as may be desired. The fine material is suitable for reuse as the abrasive to be discharged through the nozzle 31 and is therefore periodically delivered from the trap or collecting box 56 into the hopper 27. The sand box or collecting trap 56 is so shaped and related to the duct 55 leading thereto, that the material entering the duct freely passes to the collecting box, but having once entered the latter it will not readily return to the duct. The course of the sand in passing from the screening chamber to the trap or collecting box 56 is indicated in Figs. 8 to 10.

The trap or collecting box rotates with the drum and periodically passes above a chute 43 leading to the sand hopper 27, and when in position above such chute the material that has been collected and trapped in the box is permitted to flow onto the chute and by it is directed into the hopper. The sand collecting box is provided with a discharge opening that is normally closed by a door 58 that is supported by a spring hinge 59 which tends to maintain the door closed at all times except when the sand which has collected in the box is to be discharged. The face of the door 58 has secured to it a pad 62 which, closing against the casing surrounding the opening, seals the same and prevents the escape of dust and other material so long as the door is held closed. An arm 60 is connected with the door and projects outward so that it comes into engagement with a stop 65 carried by the sand hopper 27 or some other suitable part of the apparatus, the arrangement being such that as the drum revolves and the sand trap or box 56 comes to position above the chute 43 leading to the sand hopper, the arm 60 engages with the stop 65 and causes the door to be swung away from the opening 57, whereupon the sand contained in the box 56 discharges upon the chute and is thereby conducted into the sand hopper 27. The continued rotation of the drum, very shortly after the sand has been discharged as just described, carries the arm 60 beyond the stop 65, when the spring hinge 59 immediately closes the door 58. It will be observed that in a machine constructed according to my invention there is no mechanism for elevating, transporting or cleaning the sand, located within the cleaning chamber of the drum, nor are there buckets, elevators, or conveyors located outside the drum for collecting the sand and delivering it to the sand hopper for use a second time. The cleaning and grading means move with the drum, are concentric therewith so as to take up but little space, and do not have moving parts that are liable to get out of order.

It may be noted that the sand hopper 27 is located outside of the drum and at an ele-

vation above the sand blast mechanism, so that the abrasive material will be fed by gravity to the sand blast mechanism and that also the operation of the feeding of the 5 abrasive may be readily observed in order that any obstruction to the feeding operation may be noted and removed.

I herein employ the word "sand" in an inclusive sense, intending to cover thereby 10 any suitable pulverulent abrading or cleaning material adapted to be conveyed by a current of air, and when acting on the articles being agitated within the drum will assist in cleaning them.

15 What I claim is:

1. In a cleaning machine, the combination of a rotatable tumbling drum one end of which is open, supported so as to be tilted about an axis located between the ends of 20 the drum, a support for arresting and supporting the drum in a determined position for rotation and a hinged closure for the open end of the drum supported independently of the drum.

25 2. In a cleaning machine, a rotatable tumbling drum of frusto-conical shape, open at its larger end, supports for the drum to permit it to be tilted for discharging its contents, a closure for the open end of the drum 30 and supports for the closure permitting it to be moved away from the end of the drum leaving the latter entirely open.

3. In a cleaning machine, a rotatable tumbling drum open at one end, supports for the 35 drum located near the open end thereof, and adapted to permit the drum to be tilted for discharging purposes, a support for the end of the drum which is opposite the open end to hold it in position to be rotated, the support being separable to permit the tilting of the drum and a closure for the open end of the drum supported so it may be moved away from the drum to leave the end thereof 40 open.

45 4. In a cleaning machine, a rotatable tumbling drum, one end of which is open, a rocking cradle located between the ends of the drum and nearer the open end thereof, in which the drum is supported for rotation, 50 an axial bearing for supporting the end of the drum opposite the open end, such bearing being independent of the cradle and separable from its own support to permit the drum to be tilted and a closure for the open end of the drum.

5. In a cleaning machine, a rotatable tumbling drum one end of which is open and the other closed, a cradle in which the drum is supported for rotation, mounted so it may 60 be rocked to permit the drum to be tilted for discharge, an axial bearing for the drum at the closed end thereof, separable from its own support a closure for the open end of the drum, and an axial bearing for the closure.

6. In a cleaning machine, a rotatable tumbling drum, having one end open and the other closed, a support for the drum located between its ends and adapted to swing about a transverse axis to permit the drum 70 to be tilted so it may be discharged through its open end, a support for the closed end of the drum, such support having an axial bearing and being separable to permit the end of the drum to be moved away therefrom when the drum is tilted. 75

7. In a cleaning machine, a rotatable tumbling drum having one end open and the other closed, a cradle in which the drum rests and turns, supported upon an axis 80 transverse to the drum and located nearer the open end thereof, and a separable support for the closed end of the drum carrying an axial bearing for the latter.

8. The combination stated in claim 7, including also a closure for the open end of the drum and provided with an axial bearing. 85

9. In a cleaning machine, a rotatable tumbling drum having an open end, a removable closure for the open end of the drum, axial bearings at the opposite ends of the drum, one being carried by the removable closure, sand blast mechanism delivering into the interior of the drum through one of the bearings, and exhaust mechanism connected with the interior of the drum through the other of the bearings. 90

10. In a cleaning machine, a rotatable drum, having one end open and the other closed, a removable closure for the open end of the drum, a swinging bracket carrying the closure, axial bearings at the opposite ends of the drum, one set of bearings being carried by the closure and its supporting bracket, sand blast mechanism delivering into the drum through one of the axial bearings and exhaust mechanism connected with the interior of the drum through the other axial bearing. 100

105 11. The combination stated in claim 10, including also means for rotating the drum and supporting it so it may be tilted on a transverse axis for discharge when the closure is moved to open the end of the drum. 115

12. In a cleaning machine, a rotatable open-ended drum, a closure for such end of the drum provided with an axial hub, a swinging bracket supporting the closure and provided with a bearing in which the hub of the closure turns, the hub having an axial opening through it, and a sand blast nozzle located in the opening through the hub, delivering into the interior of the drum. 120

125 13. The combination stated in claim 12, including also a sand hopper delivering to the blast nozzle and supported by the bracket that carries the closure. 130

14. In a cleaning machine, a rotatable

tumbling drum, a sand blast mechanism discharging into the drum at one end, an axial tubular hub at the opposite end of the drum communicating with the interior of the latter, exhaust mechanism connected with the said tubular hub, a bearing in which the tubular hub turns, a floor stand, and a support for the said bearing having separable engagement with the floor stand, whereby 10 the drum may be tilted upon its transverse axis and the rear bearing and its support lifted away from the floor stand.

15. In a cleaning machine, a rotatable tumbling drum, a blast mechanism for delivering a cleaning abrasive into the interior of the drum, a hopper for the abrasive located exterior to the drum, a casing surrounding and turning therewith communicating with the interior of the drum and 20 into which the abrasive delivered into the drum accumulates, means within the casing for grading the abrasive that collects therein, and means whereby the graded material may be delivered from the said chamber to the exterior hopper.

16. In a cleaning machine, a rotatable tumbling drum having a perforate peripheral section, a sand blast mechanism delivering into the interior of the drum, a sand 30 hopper located exterior to the drum and arranged to deliver by gravity to the sand blast mechanism, a casing surrounding the drum, covering the perforate portion thereof and forming a closed chamber, the sand 35 and fine material from the interior of the drum being adapted to pass through the perforate portion thereof into the said chamber, and means within the said chamber and turning with the drum for sifting the material that enters the chamber and 40 delivering the fine material to the sand hopper and the coarser separated material in another direction for discharge.

17. In a cleaning machine, a rotatable 45 tumbling drum having a perforate peripheral section, sand blast mechanism for delivering into the interior of the drum, a closed casing covering the perforate portion of the drum and rotating therewith, the casing enclosing a chamber into which the sand and fine material from the interior of the drum pass, through the said perforate portion, and means in the said chamber for sifting 50 and grading the fine material that enters the chamber and operating by the rotation of the drum.

18. In a cleaning machine, a rotating tumbling drum having a perforate portion, a sand blast mechanism delivering into the 60 drum, a casing surrounding the perforate portion of the drum, and turning therewith, the casing enclosing a chamber into which passes the sand and fine material from the interior of the drum, through the perforate portion thereof, a sieve in the casing, carried

by the drum, the material in the chamber being by the rotation of the drum directed against the sieve, means for directing the material that passes through the sieve along one course, and that which does not pass 70 through the sieve along another course.

19. In a cleaning machine, a rotatable tumbling drum having a perforate portion, a sand blast mechanism delivering into the drum, and exterior thereto a sand hopper supported near the drum and delivering to the sand blast mechanism, a casing surrounding the drum and forming a chamber into which the loose sand and fine material within the drum pass, through the said perforate portion thereof, means in the said chamber for grading the sand and fine material, and means turning with the drum for directing the sand and material suitable for reuse from the said chamber to the sand 80 hopper.

20. In a cleaning machine, a tumbling drum having a perforate portion, a sand blast mechanism delivering into the drum, a sand hopper located in proximity to the drum and delivering to the sand blast mechanism, a casing surrounding the drum and rotating therewith enclosing a chamber into which the loose sand and fine material collected in the drum pass, through the said 90 perforate portion of the drum, means rotating with the drum for grading the material that passes to the said chamber, and means for delivering that part of the graded material capable of reuse to the sand hopper. 95

21. In a cleaning machine, a tumbling drum having a perforate portion, a sand blast mechanism delivering into the drum, a sand hopper located in proximity to the drum and delivering to the sand blast mechanism, a casing surrounding the drum and rotating therewith enclosing a chamber into which the loose sand and fine material collected in the drum pass, through the said 100 perforate portion of the drum, means rotating with the drum for grading the material that passes to the said chamber, a collecting receptacle that turns with the drum means for delivering that part of the graded material capable of reuse to said collecting 105 receptacle, and means for periodically discharging such receptacle so its contents pass to the sand hopper.

22. In a cleaning machine, a rotatable tumbling drum having a perforate portion, a sand blast mechanism delivering thereto, a casing surrounding the drum and turning therewith forming a chamber covering the perforate portion of the drum, means for grading the loose material that passes from the drum into the chamber, through the perforate portion of the former, comprising a sieve across which the material is caused to move by the rotation of the drum, and means for directing 125

the material passing through the sieve along one course and that which does not pass through the sieve along another course.

23. In a cleaning machine, a rotatable 5 tumbling drum having a perforate portion, a sand blast mechanism delivering thereto, a casing surrounding the drum and turning therewith forming a chamber covering the perforate portion of the drum, means for 10 grading the loose material that passes from the drum into the chamber, through the perforate portion of the former, comprising a sieve across which the material is caused to move by the rotation of the drum, a second 15 sieve reversely inclined as to the first which receives the material that does not pass through the first sieve, and means for directing the material passing through the two sieves to a common collecting receptacle and 20 the material which does not pass through the sieves to another collecting receptacle.

24. In a cleaning machine, a rotatable tumbling drum having a perforate portion, a sand blast mechanism delivering thereto, a 25 casing surrounding the drum and turning therewith forming a chamber covering the perforate portion of the drum, means for grading the loose material that passes from the drum into the chamber, through the perforate portion of the former, comprising a sieve across which the material is caused to move by the rotation of the drum, a collecting receptacle rotating with the drum, means for directing to 30 said receptacle the sifted material, and means operated by the rotation of the drum for periodically discharging the said collecting receptacle, permitting its contents to pass to the said hopper.

move by the rotation of the drum, a collecting receptacle that turns with the drum, means for directing the material that passes through the sieve to said collecting receptacle, means for directing the material that does not pass through the sieve along another course, and means for periodically discharging the sifted material that collects in the said receptacle. 35 40

25. In a cleaning machine, the combination of a rotatable tumbling drum having a perforate portion, a sand blast mechanism delivering thereto, a sand hopper supported near the drum and delivering to the sand blast mechanism, a casing surrounding the drum and turning therewith forming a chamber covering the perforate portion of the drum, means for grading the loose material that passes from the drum into the chamber, through the perforate portion of the former, comprising a sieve across which the material is caused to move by the rotation of the drum, a collecting receptacle rotating with the drum, means for directing to said receptacle the sifted material, and means operated by the rotation of the drum for periodically discharging the said collecting receptacle, permitting its contents to pass to the said hopper. 45 50 55

JOSEPH P. WILD.
